[57] ABSTRACT

A composite transport vehicle comprises a large enclosed electric induction apparatus supported between bell crank end frames. The end frames carried on separate wheel trucks and pivoted to opposite lower ends of the apparatus casing. Tensile stress between the end frame pivots is transferred to the casing base and a transverse end wall rib by vertical bearing brackets therebetween; compressive stress at opposite upper ends of the casing is transferred to the internal magnetic core clamps through internal blocking between core and casing.

TRANSPORT VEHICLE FOR LARGE ENCLOSED ELECTRIC INDUCTION APPARATUS

Our invention relates to vehicles for rail or roadway transport of large enclosed electric induction apparatus such as power transformers, reactors and the like. More particularly the invention concerns improved means for incorporating large enclosed electrical apparatus as part of a transport vehicle structure. The following art, which appears to be prior to applicant's invention and may be regarded as relevant, has been specifically considered by applicant:

U.S. Pat. 3,242,879 — Bronlund
 U.S. Pat. 3,147,715 — Myers
 U.S. Pat. 3,143,082 — Austgen
 U.S. Pat. 3,116,086 — Barendoltz
 U.S. Pat. 3,164,973 — Aronson
 U.S. Pat. 2,341,903 — Cholewa
 U.S. Pat. 3,401,648 — Gutridge
 U.S. Pat. 3,273,516 — Trumper et al
 U.S. Pat. 3,075,478 — Elsner
 U.S. Pat. 3,059,886 — Lord

It is also previously known to support a large power transformer for transport between two longitudinally spaced bell crank carrying frames which are pivotally fixed to the transformer tank at opposite lower ends thereof and carried upon separate swiveled wheel trucks, the carrying frames bearing in compression upon opposite upper ends of the transformer tank. Such a dual bell crank carrying frame assembly is referred to as a "Schnabel Car," and in such a structure the bell crank frames impose severe tension and compression forces upon the transformer tank.

Heretofore in designing transformer tanks for incorporation into Schnabel type transport cars it has been the practice to incorporate in the tank structure special tension bars extending between the bell crank pivots and special compression ribs extending between the longitudinally spaced upper clamping or compression points of the bell crank frames. Such special strengthening bars and ribs add appreciably to tank cost and are not required after a transformer is installed for operation on a fixed foundation.

Accordingly, it is a principal object of our invention to provide a transport vehicle including a large enclosed electric induction apparatus wherein the incorporated load is so connected to a pair of bell crank carrying frames that special longitudinal reenforcement of the load enclosure for transport is unnecessary or minimized.

It is another object of our invention to provide, in a transport vehicle including spaced apart clamping frames and an intermediate box-like load enclosure, means for pivotally connecting the frames to the load enclosure without requiring special longitudinal strengthening of the enclosure in tension or compression.

It is a more specific object of our invention to provide an improved transport vehicle for large electric power transformers and the like wherein the transformer tank and core structure are both so incorporated in the vehicle structure that special tank reenforcement is not required.

In carrying out our invention in one preferred embodiment we utilize bell crank clamping and supporting frames of the "Schnabel Car" type and incorporate between them as part of an assembled vehicle a large

electric power induction apparatus comprising a core and coil assembly within a box-like outer enclosure set upon a rigidly reenforced base. The bell crank carrying and clamping frames are pivotally connected to the load enclosure by pivot means mounted in rigid end brackets. These brackets transfer the tensile forces to the tank base directly and to the sidewalls through reinforcing ribs which extend transversely across the tank end walls near the base. At the upper end wall regions engaged in compression between the bell crank frames we provide back-up support for the tank end walls by utilizing the core structure of the enclosed induction apparatus. To this end we provide removable blocking means internally of the tank between the end walls and upper yoke clamps of the magnetic core.

Our invention will be more fully understood and its objects and advantages further appreciated by referring now to the following specification, taken in conjunction with the attached drawing, in which:

20 FIG. 1 is a side elevational view of a large enclosed electric power transformer mounted upon wheeled swivel trucks to constitute a transport vehicle embodying our invention;

25 FIG. 2 is an end elevational view of the transformer enclosing tank;

FIG. 3 is a fragmentary perspective view of one lower end portion of the transformer tank; and

30 FIG. 4 is an enlarged fragmentary cross sectional view of a dual swivel joint or truck pivot illustrated at FIG. 1.

Referring now to the drawing, and particularly to FIG. 1 we have illustrated a large enclosed electric power transformer 1 mounted upon a pair of swiveled wheel trucks or bogies 2 by means of a pair of bell crank carrying frames 3 pivotally connected to opposite lower ends of the transformer tank. The swiveled bogie trucks 2 are shown as multiple axle trucks each having a horizontal bolster plate or platform 4 upon which a horizontal side arm of one bell crank frame 3 is pivotally mounted. Each carrying frame 3 is connected to a lower end portion of the transformer tank by transverse pivotal means (shown as a single pivot pin 5) and has a vertical side arm which bears at its upper end against a pair of compression plates 6 on each end wall of the transformer tank. Horizontal swiveling movement of each truck 2 with respect to the carrying frame 3 mounted thereon takes place about one or the other of two longitudinally spaced apart swivel pins, or vertical pivots, between the juxtaposed frame 3 and truck platform 4, as will be more fully described hereinafter.

The transformer 1 comprises a large substantially rectilinear enclosing tank 10 which includes a rigid base plate 10a and longitudinally spaced apart end walls 11. As illustrated at FIG. 2, the tank 10 includes also substantially parallel spaced apart side walls 12 which are inclined inwardly toward the base at their lower regions 12a.

60 The power transformer within the enclosing tank 10 is illustrated as a large three phase power transformer including a magnetizable core made up of three vertical coil carrying legs 15 magnetically coupled together through upper and lower horizontal yokes 16 and 17 respectively. The horizontal core yokes are each clamped between a pair of long sectional beams or yoke clamps 18 extending in laterally spaced parallel relation beyond the yokes into close proximity with the

tank end walls 11. Each coil carrying leg 15 is surrounded by a toroidal coil assembly 20 which includes primary and secondary windings for one phase of a three phase circuit. It will of course be understood by those skilled in the art that a three-legged, three phase transformer is shown by way of illustration and that the invention is equally applicable to large power transformers of other types as well as to large reactors and the like.

As illustrated at FIG. 3 the tank base 10a comprises a base plate 30 rigidly reenforced on the outer surface by a rigid frame of sectional beams comprising side beams 31 and transverse beams 32. The tank end walls 11 are inset from the extreme longitudinal end of the base 10a and are reenforced by a single transverse sectional rib 33 above and parallel to the tank base 10a. As illustrated, the inclined side wall portions 12a extend upwardly from the base to a point near the bottom of the coils 20, and the transverse end wall reenforcing rib 33 is located at about the same vertical position.

Large electric power transformers of the type illustrated may have a dry weight of the order of several hundred tons and are long relative to their height. It is evident that bell crank carrying frames 3, pivotally mounted on the pins 5 and bearing in compression on the tank end walls at the plates 6, exert extremely high tensile force between opposite lower ends of the tank and high compressive force between opposite upper ends of the tank. In prior transport vehicles which utilize bell crank carrying frames of the type illustrated it has been the practice to strengthen the tank to resist these forces by providing longitudinal side wall braces additional to those required for side wall rigidity in the normal operation of the transformer. Long and massive reenforcing ribs which are needed only for transport add appreciable expense to the tank structure. By our invention we propose to eliminate need for such special longitudinal reenforcement in transport. This we do by referring the tensile force between frames 3 to the rigid tank base and to the sidewalls, and transferring the compressive or clamping force between the frames 3 to the top yoke clamps.

The manner in which our invention transfers the tensile and compressive forces between the carrying frames 3 is illustrated at FIGS. 1 and 3. To resist tensile force between the pivot pin 5 the tank base 10a extends at each end beyond the end wall 11 and a pair of vertical bearing brackets 35 are connected between the base and the transverse rib 33 and in parallel spaced apart relation perpendicular to the end wall. In the illustrated embodiment of the invention wherein the lower portions 12a of the tank side walls are tapered inwardly the bearing brackets 35 are set at the outer extremities of the base 10a and thus inset from the parallel side wall portions 12. Each bearing bracket 35 is provided near its lower end, and thus near the base 10a, with a pivot bearing 36 for receiving the carrying frame pivot pin 5. It will be understood by those skilled in the art that if desired separate and aligned transverse pivot pins may be utilized in the laterally apaced pivot bearings 36.

To resist the compressive clamping force applied by the carrying frames 3 against the plates 6 at opposite upper ends of the transformer tank we utilize the rigid upper yoke clamps 18. These yoke clamps are placed in compression between the tank end walls by provid-

ing removable blocks or spacers 40 (FIG. 1) in the space between each end wall and the proximate ends of the yoke clamps. The spacers 40, preferably formed of metal or other material strong in compression, are not a part of the operative transformer structure; optionally they may be removed or left in position in normal electrical operation of the transformer after transport has been completed.

For purpose of illustration we have shown the horizontal side arms of the bell crank carrying frames 3 resting upon multiple axial wheeled trucks 2 and pivotally connected thereto for horizontal swiveling action about vertical pivots. The vertical pivoting or swivel action illustrated at FIGS. 1 and 4, while not constituting a part of our present invention, provides between each carrying frame 3 and its associated bogie truck 2 a normal pivot point located substantially at the longitudinal midpoint of the truck and an alternate longitudinally inset, or "reduced," pivot point which may optionally be utilized to reduce lateral offset of the transformer 1 with respect to the center line of a curved road bed. As is well known to those skilled in the art, it is sometimes necessary on sharp curves to limit lateral offset at the midpoint of a long vehicle in order to clear lateral obstacles. Such a dual, or selectable, pivoting arrangement between truck and carrying frame is illustrated more particularly at FIG. 4.

Referring now to FIG. 4 the flat horizontal truck platform 4 is provided at its longitudinal and transverse midpoint with a bearing recess 41. A flat bearing plate 42 rests upon the platform 40 and includes a vertical swivel pin 42a extending downwardly into the recess 41 of the truck platform. The bearing plate 42 extends longitudinally inward (i.e., toward the vehicle midpoint) from the pivotal connection 41, 41a and includes on its upper surface a second vertical swivel pin 42b positioned on the longitudinal axis of the truck 2 and offset inwardly from the pin 42a. The horizontal side arm of the carrying frame 3 rests upon the top of the bearing plate 42 and includes a bearing recess 43 into which the swivel pin 42b extends. Thus the bearing plate 42, interposed in flatwise relation between the truck platform 4 and carrying frame 3, is pivotally connected to the truck platform through the swivel pin 42a and to the bearing frame 3 through the swivel pin 42b.

The two longitudinally spaced swivel pins provided between each wheeled truck 2 and its associated carrying frame 3 are arranged to be rendered alternatively operable to permit horizontal swiveling movement between the truck and frame. For this purpose selectable locking means are provided to prevent swiveling movement between bearing plate 42 and the carrying frame 3 or, alternatively, between the bearing plate 42 and the truck platform 4. Such locking means have been indicated schematically as pins 50 and 51, respectively, at opposite ends of the plate 42. While these pins 50, 51 are illustrated in the drawing as both in place, it is to be understood that in operation either one or the other of the pins will be removed, thereby to permit swiveling movement between the truck 2 and the carrying frame 3 about that pivot pin (42a or 42b) which engages the part not locked to the plate 42. In such pivotal movement it will be evident that arcuate sliding movement occurs between the bearing plate 42 and that part (i.e., truck 2 or frame 3, as the case may be) from which the locking pin has been removed. It will now be evident that in this manner either the swivel pin

42a or the swivel pin 42b may be selected as the vertical pivot between each carrying frame 3 and its associated bogie truck.

The longitudinally offset selectable truck pivot described above is claimed in a copending patent application Ser. No. 251,154 filed May 8, 1972 by Stanley H. Wilk and assigned to the same assignee as the present application. (Docket 11PT03314).

While we have described a single embodiment of our invention by way of illustration, many modifications will occur to those skilled in the art, and we therefore wish to have it understood that we intend in the appended claims to cover all such modifications as fall within the true spirit and scope of our invention.

What we claim as new and desire to secure by Letters Patent of the United States is:

1. A large enclosed electric induction apparatus, a pair of longitudinally spaced bell crank carrying frames mounted upon separate swiveled wheel trucks, said induction apparatus comprising an elongate enclosing casing having substantially vertical end walls in parallel spaced relation, a rectangular magnetic core including at least two vertical legs extending between horizontal upper and lower yokes, a pair of rigid laterally spaced yoke clamps extending along opposite sides of at least said upper core yoke and into close proximity to said end walls, a current carrying coil mounted upon at least one said vertical leg and having an outer diameter greater than the lateral spacing between said yoke clamps, blocking members interposed between each said end wall and the proximate ends of said yoke clamps internally of said casing, and axially transverse pivotal means fixed to opposite lower end portions of said casing, said bell crank frames being pivotally mounted upon said pivotal means and having vertical arms engaging said end walls in clamping relation externally adjacent said blocking members.

2. A large enclosed induction apparatus, a pair of longitudinally spaced apart bell crank carrying frames mounted upon separate swiveled wheel trucks, said induction apparatus comprising an elongated enclosing casing having substantially vertical end walls in parallel spaced apart relation and a rigidly reenforced horizontal base extending at each end beyond said end walls, a transverse reenforcing member extending across each said end wall in a lower region proximate said base, and axially transverse pivotal mounting means connected between said base and said reenforcing member externally adjacent each said end wall, said bell crank frames being pivotally mounted upon said pivotal mounting means and having vertical arms engaging upper regions of said end walls in clamping relation, said pivotal mounting means transferring tensile stress therebetween to said base and to said transverse member.

3. An enclosed electric induction apparatus according to claim 2 wherein said pivotal mounting means comprises a pair of bearing brackets extending vertically in parallel spaced relation adjacent each said end wall, each said bearing bracket being connected at one end to said base and at the other end to said transverse

member.

4. A large enclosed electric induction apparatus, a pair of longitudinally spaced apart bell crank carrying frames mounted upon separate swiveled wheel trucks, said induction apparatus comprising an elongate enclosing casing having substantially vertical end walls in parallel spaced apart relation and a rigidly reenforced horizontal base extending at each end beyond said end walls, a rectangular magnetic core having at least two vertical legs extending between horizontal upper and lower yokes, a pair of rigid laterally spaced yoke clamps extending along opposite sides of at least said upper core yoke within said casing and into close proximity to said casing end walls, a current carrying coil mounted upon at least one said vertical leg and having an outer diameter greater than the lateral spacing between said yoke clamps, removable blocking members interposed between each said end wall and the proximate ends of said yoke clamps, a transverse reenforcing member extending across each said end wall in a lower region proximate said base, pivotal mounting means connected between said base and said reenforcing member externally adjacent each said end wall, said bell crank frames being pivotally mounted upon said mounting means and having vertical arms engaging upper regions of said end walls in clamping relation externally adjacent said removable blocking members, said pivotal mounting means transferring tensile stress therebetween to said base and to said transverse reenforcing member.

5. An electric induction apparatus according to claim 4 wherein said enclosing casing comprises spaced apart side walls having lower portions inclined downwardly and inwardly beneath the lower end of said current carrying coil and said transverse reenforcing member extends across said end walls at approximately the upper limit of said inclined side wall portions.

6. In combination a large electric power transformer including a core and coil assembly mounted upon a rigid base and an enclosing casing including said base and having parallel spaced apart vertical end walls, said core and coil assembly including upper and lower pairs of horizontal yoke clamps having opposite ends internally adjacent said end walls, removable blocking means interposed between said end walls and the upper pair of said yoke clamps, a pair of bell crank carrying frames pivotally mounted upon said casing at opposite lower ends adjacent said base, said bell crank frames having vertical arms engaging said end walls externally adjacent said blocking means and having horizontal arms, and a swiveled bogie truck positioned in supporting relation between each said horizontal frame arm.

7. The combination according to claim 6 wherein said base extends longitudinally beyond each said end wall and each said bell crank frame is pivotally mounted upon a pair of bearing brackets fixed to said base and extending vertically along one said end wall in parallel spaced apart relation.
